UNITED STATES PATENT OFFICE

FRED FACHNIE, OF WITHROW, WASHINGTON

WATER MOTOR

Application filed February 7, 1929. Serial No. 338,219.

This invention relates to water motors, and more particularly to a water motor intended for operation by the current of a running stream.

5 An important object of the invention is to provide a device of this character which may be readily and cheaply manufactured and which will provide an efficient and durable motor structure delivering a smooth even 10 power drive at a desired point.

A further object of the invention is to provide a device of this character where the construction is such that the blades are always assured of proper submergence and 15 means are provided for preventing accidental disengagement of these blades with the bottom of the stream.

These and other objects I attain by the construction shown in the accompanying drawings, wherein for the purpose of illustration is shown a preferred embodiment of my invention and wherein:—

Figure 1 is a side elevation of a water motor constructed in accordance with my invention;

Figure 2 is a sectional view therethrough;

Figure 3 is a sectional view through the propeller shaft;

Figure 4 is a longitudinal sectional view 30 through the propeller shaft showing the means of securing the blades in position thereon.

Referring now more particularly to the drawings, the numeral 10 generally designates a raft, which is preferably in the form of parallel pontoon elements 11 connected adjacent their forward and rear ends by braces 12, which maintain the elements in a predetermined spaced relation. The forward 35 ends of these elements will be provided with any suitable means to permit the raft to be secured to anchors or the bank of a stream, as desired. Extending downwardly from the pontoon elements adjacent the forward and rear ends thereof are convergent braces 13, the lower ends of which have secured thereto bearings 14 within which operate a horizontal shaft 15. The forward bearing 14 is preferably connected with the pontoon elements 40 by upwardly and forwardly inclining braces,

indicated at 15. The forward end of the shaft is connected in any suitable manner as, for example, by chain and sprocket gearing illustrated at 16 with a shaft 17 mounted in bearings 18 carried by the forward braces 55 12. This shaft 17 is at present illustrated as having a pulley 18^a attached thereto and is hereinafter referred to as a power take-off shaft.

Secured to the shaft are a plurality of 60 blades 19, these blades being uniformly spaced along the shaft between the bearings and each comprising a straight strip of material, the central portion 20 of which is perpendicularly related to the shaft and the 65 end portions 21 of which are oppositely flexed or twisted to place them at an angle of between 5° and 10° to such central portion. Adjacent blades are disposed at substantially 70 right angles to one another, the variation from a right angle being such that the entire series of blades is uniformly spaced about the shaft and each blade is insofar as possible removed from the path of a succeeding blade. 75

Disposition of the blades in this manner prevents the current flow from being disturbed to such an extent that the side slip of the current against the blade does not interfere with proper action of the current 80 upon the next succeeding blade and by employing a small angle or pitch for the blade, the thrust obtainable is increased and the operation of the shaft steadied. Blades of this character may be very readily manufactured and in event anything comes in contact therewith causing the blade to become 85 bent, may be very readily straightened.

In order to insure the blades against contact with the bottom of the stream, due to 90 reduction in the level thereof, I secure to opposite ends of the pontoons rigid leg elements 22, the lower ends of which are arranged in a plane paralleling the pontoons and below the path of movement of the 95 blades. These legs, in event the stream lowers to a predetermined extent, will engage upon the bottom thereof, supporting the pontoons and thus prevent the blades from being damaged. Since the blades are at all 100

times submerged, the current action is obtained thereon through the entire 180° of their rotation and there is no period of inoperative movement as in most water motors.

As a convenient means of attaching the blades and the sprocket to the shaft 15, this shaft is made composite, comprising an inner rod 22 surrounded by a series of sleeve elements 23. Nuts 24 at opposite ends of the rod serve as a means for compacting the sleeve elements and causing them to grip washers 25 disposed at opposite sides of the sprocket of the shaft and at opposite sides of the various blade elements.

Each blade element is formed with a central opening 26 for the passage of the rod 22. This structure further facilitates maintenance of the shaft against longitudinal movement, as certain of the sleeve elements which extend through the bearings 14 may be made of the same length as the width of these bearings and washers 27 disposed at opposite ends thereof which are of greater diameter than the bearing and which accordingly engage opposite end faces of the bearing to hold the shaft in its proper position. This structure not only maintains the shaft against movement but provides a structure wherein any of the elements may be very readily replaced and the sleeves which actually form the wearing surface coacting with the bearings may be readily replaced in event any looseness occurs at this point.

Since the construction hereinbefore set forth is capable of a certain range of change and modification without materially departing from the spirit of the invention, I do not limit myself thereto except as herein-after claimed.

I claim:—

A water motor of the character described comprising in combination, a pair of pontoons, a pair of bearings dependingly secured to said pontoons and adapted to be positioned in a stream of running water, a shaft loosely mounted in said bearings, a sleeve positioned about said shaft and engaging said bearings, said sleeve comprising a plurality of intermediate sections, a plurality of propeller blades loosely mounted on said shaft and positioned between said intermediate sleeve sections, said shaft having threaded opposite end portions, a nut threadably positioned on each end of said shaft and adapted to force said sleeve sections inwardly whereby to cause said sleeve sections to rotate coaxively with the rotation of said blades, a sprocket member mounted on one of said sleeve sections, a driven member mounted on said pontoons and connected to said sprocket, flexible means connected to said sprocket on said sleeve and said driven member whereby to rotate said driven member cooperatively with the rotation of said sprocket, and guard means dependingly se-

cured to the bottom of said pontoons adjacent each end and in spaced relation to each other whereby to hold said blades out of engagement with the bottom of the stream.

In testimony whereof I hereunto affix my signature.

FRED FACHNIE.
